CLAIM

The ornamental design for the lighting fixture, as shown and described.

DESCRIPTION

FIG. 1 is a perspective view of a first embodiment of the design;

FIG. 2 is a top view of the embodiment of FIG. 1;

FIG. 3 is a side view of the embodiment of FIG. 1;

FIG. 4 is a bottom view of the embodiment of FIG. 1;

FIG. 5 is a front view of the embodiment of FIG. 1; and

FIG. 6 is a rear view of the embodiment of FIG. 1.

FIG. 7 is a perspective view of a second embodiment of the design;

FIG. 8 is a top view of the embodiment of FIG. 7

FIG. 9 is a side view of the embodiment of FIG. 7;

FIG. 10 is a bottom view of the embodiment of FIG. 7;

FIG. 11 is a front view of the embodiment of FIG. 7;

FIG. 12 is a rear view of the embodiment of FIG. 7.

FIG. 13 is a perspective view of a third embodiment of the design;

FIG. 14 is a top view of the embodiment of FIG. 13;

FIG. 15 is a side view of the embodiment of FIG. 13;

FIG. 16 is a bottom view of the embodiment of FIG. 13;

FIG. 17 is a front view of the embodiment of FIG. 13; and,

FIG. 18 is a rear view of the embodiment of FIG. 13.

The broken lines shown on the drawings depict portions of the lighting fixture that form no part of the claimed design.

1 Claim, 14 Drawing Sheets
